HIS ATTORNEYS.

UNITED STATES PATENT OFFICE

112,011

DESIGN FOR A PUMP

Sol J. Waxelbaum, Atlanta, Ga.

Application March 26, 1938, Serial No. 76,112

Term of patent 3½ years

To all whom it may concern:

Be it known that I, Sol J. Waxelbaum, a citizen of the United States, and a resident of the city of Atlanta, in the county of Fulton and State of Georgia, have invented a new, original, and ornamental Design for a Pump, of which the following is a specification, reference being had to the accompanying drawing, forming part thereof.

Figs. 1 and 2 are perspective views of a pump showing my new design.

I claim:

The ornamental design for a pump, as shown.

SOL J. WAXELBAUM.
